UNITED STATES PATENT OFFICE.

JASPER L. PURPLE, OF OWEGO, NEW YORK.

SAW.

SPECIFICATION forming part of Letters Patent No. 309,646, dated December 23, 1884.

Application filed May 6, 1884. (No model.)

To all whom it may concern:

Be it known that I, JASPER L. PURPLE, of Owego, in the county of Tioga and State of New York, have invented a new and Improved Saw, of which the following is a full, clear, and exact description.

The object of my invention is to provide a new and improved saw which is so constructed that it can also be used as a square, plumb, bevel, &c.

The invention consists in a saw having a longitudinal slot at right angles to the straight inner edge of the handle, through which slot a set-screw passes, which can be adapted to any desired angle, one edge of the slot being provided with a graduated angle-scale, while the lower inner corner edge of the handle is adapted to serve as a rest for a straight-edge, rule, or analogous instrument.

Reference is to be had to the accompanying drawings, forming part of this specification, in which similar letters of reference indicate corresponding parts in both the figures.

Figure 1 is a side view of the handle end of my improved saw, parts being broken out. Fig. 2 is a top view of the same.

The saw-blade A is secured at its butt-end to a handle, B, in the usual manner. This handle is provided on its inner end with a straight-edge, which is at right angles to the back edge of the saw, or to a longitudinal slot, C, with the said back edge. A screw, D, is held in that corner of the handle toward the cutting-edge, and a recess, E, is formed on the upper inner corner, and into the said recess the end of the slot passes. The recess E is of such depth that the head of a screw, F, can be held entirely within the recess, so that the said head does not project beyond the inner straight-edge of the saw-handle. The screw F passes through the slot C, and is adapted to be moved in the same in the di-

rection of the slot. Along the inner edges of the slot C lines are cut, etched, or otherwise produced, which indicate the inclination from zero to forty-five degrees. In the inner edge of the saw-handle a glass level-tube, G, is held. As shown in Fig. 1, the inner edge of the handle B is adjusted at right angles to the slot C. If a different angle is desired, the screw F is moved more or less in the direction of the arrow a', and a straight-edge, rule, &c., placed against the heads of the screws D and F have the desired inclination, as shown in dotted lines in Fig. 1. If the saw is placed with its back against an upright, it can be used as a plumb, and if held in a horizontal position it can be used as a level.

I am aware that it is old to provide the blade with a graduated arc and with a pivoted bevel-arm having a bevel-link, said bevel-arm registering with the graduations of said arc; to provide the blade with pivoted angular pieces having a clamping-screw adjustable in a straight slot in the blade, and with a graduated arc, and to provide the blade with pivoted bevel-beams having a clamping-screw adjustable in a segmental slot in said blade, and with a graduated arc.

Having thus described my invention, I claim as new and desire to secure by Letters Patent—

The combination, with a saw with its blade provided with a straight longitudinal slot, along one edge of which are arranged angle-graduations, of the set-screw adjustable in said slot, and adapted to serve, together with the lower inner corner edge of the handle, as a rest for a straight-edge, rule, or analogous instrument, substantially as set forth.

JASPER L. PURPLE.
